(57) CLAIM

The ornamental design for a bubble bottle with spill proof cap, as shown and described.

DESCRIPTION

FIG. 1 is a perspective view of a bubble bottle with spill proof cap, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrated in the drawing views are included to show unclaimed environment only and form no part of the claimed design. The dot-dash lines represent the boundaries of the claim and form no part thereof.
